Inventor

UNITED STATES PATENT OFFICE.

JOHN F. PENN, OF BALTIMORE, MARYLAND.

AEROPLANE.

Application filed March 14, 1924. Serial No. 699,160.

To all whom it may concern:

Be it known that I, JOHN F. PENN, a citizen of the United States, residing at Baltimore city, State of Maryland, have invented certain new and useful Improvements in Aeroplanes, of which the following is a specification.

This invention relates to aeroplanes, one of its objects being to provide a structure of this character having its parts so distributed that when the power is shut off, the machine can be caused to descend gradually after the manner of a parachute, thereby adding materially to safety in flight.

Another object is to so place the weight of the machine that the center of gravity will be located well below the planes, thereby enabling the car or fuselage to be utilized as a stabilizing means.

A further object is to provide means for shifting the position of the car relative to the wings to control the flight upwardly or downwardly and to enable the user to bring the machine to any position desirable for soaring.

A still further object is to provide improved means for steering the aeroplane.

With the foregoing and other objects in view which will appear as the description in proceeds, the invention consists of certain novel details of construction and combinations of parts which will be hereinafter more fully described and pointed out in the claims, it being understood that various changes may be made in the construction and arrangement of the parts without departing from the spirit of the invention as claimed.

In the accompanying drawings the preferred form of the invention has been shown.

In said drawings—

Figure 1 is a plan view of the machine.

Figure 2 is a side elevation.

Figure 3 is a front elevation.

Figure 4 is a plan view of the steering mechanism.

Figure 5 is a section on line 5—5, Figure 4.

Figure 6 is an enlarged vertical transverse section through the car taken where it is suspended from the plane structure.

Figure 7 is a section on line 7—7, Figure 6.

Figure 8 is a section on line 8—8, Figure 6.

Figure 9 is a section through one of the legs of the running gear.

Referring to the figures by characters of reference, 1 designates the central sustaining plane having depending longitudinal banking planes 2 along the sides thereof and perpendicular thereto. The lower edges of these planes 2 are suitably connected and a transverse shaft 3 is also attached to said planes. A car 4 is suspended from this shaft and has sleeves 5 secured to it. These sleeves are adapted to rotate on the shaft and extend into bearings 6. Shaft 3 is intersected by a frame 7 adapted to rotate therewith and spacing sleeves 8 are secured to the shaft and frame and abut against the sleeves 5. A motor 9 is pivotally mounted in the frame 7 and has a shaft 10 extending forwardly therefrom and over an arcuate guide rail 11 extending transversely in front of the banking planes 2 and suitably secured to them. A slide 12 is mounted on this rail, as shown in Figure 5 and constitutes a bearing for the shaft 10. A propeller 13' is connected to the front end of shaft 10.

Operating cables 13 are connected to opposite sides respectively of the slide 12 and engage guide pulleys 14 at the ends of the rail 11. From these pulleys the cables extend backwardly along converging lines to guide pulleys 15 in the car 4 and thence to a spool 16 or the like mounted for rotation in the car. A hand wheel or other suitable operating means is connected to the spool as shown at 17 and by means thereof a pull can be exerted through either cable upon the slide 12 so as to move the slide in either direction and cause the shaft 10 and its motor to swing to the right or to the left relative to the car. In this way the aeroplane can be easily guided while in flight.

One of the sleeves 5 has a disk 18 secured thereto or integral therewith provided with a series of apertures 19 adjacent the periphery thereof. Another disk 20 is integral with or secured to one of the sleeves 8 and has an arm or lever 21 extending downwardly therefrom. A bell-crank 22 is mounted on this disk 20 and has a pin 23 connected to one arm and slidably in the

disk 20. The other arm of the bell-crank is connected by a rod 24 to a hand lever 25. A spring 26 serves to hold the pin 23 normally projected into one of the openings 5 19 in disk 18 thereby to couple the two disks, as shown in Figure 6.

The running or landing gear of the aeroplane preferably consists of four legs located at the respective corners of the car 4, 10 as shown at 27. Each leg includes a tubular member secured to the car, as at 28 and housing the upper portion of a slidible member 29. A spring 30 is located in the tubular member and bears against the slidible member to constitute a cushion for the car and each slidible member has a wheel 31 mounted therein.

The main sustaining plane 1 has side sustaining planes 32 extending laterally therefrom and is also provided with a tail plane 33. The side planes are preferably provided at their outer ends with rearwardly extending portions 34. By referring to Figure 1 it will be noted that the car 4 is located under the center of the main wing 1 so that the machine is properly balanced laterally. As shown in Figures 2 and 3 the car is positioned well below the planes. Thus the center of gravity is located at a 20 point where the machine will be stabilized. In other words the car will act as a weight or pendulum to maintain the lateral balance of the aeroplane and the entire structure will be free to gravitate like a parachute 30 should the propelling force fail. By means of the lever 21, pin 23 and the disks, the car can be fastened at any desired angle relative to the planes so that the weight of the car and its contents will maintain the planes 40 at any desired angle of incidence. As before explained the shaft 10 and propeller 13' can be swung laterally to guide the machine.

Importance is attached to the use of the banking planes 2 as they act to displace air 45 laterally and downwardly when the machine

is tilted, thereby serving to prevent overturning and to increase the parachute action of the machine when descending.

What is claimed is:—

1. An aeroplane including main and side 50 sustaining planes, parallel banking planes at the sides of the main plane, and a car pivotally connected to and suspended from between the banking planes.

2. An aeroplane including main and side 55 sustaining planes, parallel banking planes at the sides of the main plane, a car suspended from between the banking planes and constituting a lateral stabilizer, a propeller shaft mounted between and extending 60 forwardly from the banking planes, and means in the car for adjusting the shaft laterally angularly.

3. An aeroplane including main and side 65 sustaining planes, parallel banking planes depending therefrom at the sides of the main plane, a car suspended from between and mounted to swing relative to the banking planes, a forwardly extending propeller shaft in front of the car, and means within 70 the car for angularly adjusting the shaft laterally relative to the car and planes.

4. An aeroplane including main and side 75 sustaining planes, parallel banking planes thereunder at the sides of the main plane, a car pivotally connected to and suspended from between the banking planes, said car constituting a lateral stabilizer, and means within the car for holding it against swinging movement relative to the planes and at 80 a desired angle relative thereto.

5. An aeroplane as set forth in claim 4 having a forwardly extending propeller shaft, an arcuate guide therefor, a motor connected to and movable with the shaft, 85 and means in the car for adjusting the shaft angularly relative to the car.

In testimony whereof I affix my signature.

JOHN F. PENN.
